SWITCHING APPARATUS

John E. Ostline, Chicago, Ill., assignor to Associated Electric Laboratories, Inc., Chicago, Ill., a corporation of Delaware

Application June 12, 1937, Serial No. 147,810

12 Claims. (Cl. 200—98)

The present invention relates to switching apparatus and more particularly to apparatus adapted for use in wire communication systems for selectively setting up connections between the various lines embodied therein.

In the usual system of this character, and notably in an automatic telephone system of any size, a considerable number of switching units are necessary for performing the various line selecting functions required in establishing desired connections between the many lines of the system. Several types of switching units for performing the above noted functions are known in the electrical arts. One form of unit which is well adapted for use in the application noted and which possesses distinct advantages with respect to the simplicity of its construction, is shown in United States Patent No. 1,201,869—Reed, granted October 17, 1916. Briefly described, the unit disclosed in this patent comprises a circuit controlling element having mounted thereon contact segments rotatable with the controlling element between two positions to make and break contact between a multiplicity of brushes or wipers, arranged in pairs respectively associated with the several segments. Means comprising a magnet having an armature or plunger arranged to actuate the circuit controlling element are provided in the unit for rotating the element between its two operating positions. While this form of switching unit is fairly satisfactory in operation, the large number of wipers bearing against the contact segments and the construction of the segments necessitates the use of a heavy duty solenoid of comparatively large size and requiring a considerable amount of power for its energization. In order to obviate this difficulty, an improved arrangement disclosed in copending application Serial No. 109,813—Obergfell, filed November 9, 1936, was developed. In the structure of the unit disclosed in this application, the elements are so constructed and arranged that less power is required to actuate the circuit controlling element embodied therein, whereby a heavy duty relay may be used for actuating this element. Although the improvements as disclosed in the Obergfell application renders a switching unit of the form just described practical from an operating standpoint, the unit is relatively expensive to manufacture, due to the cost entailed in providing the heavy duty relay. Moreover, with a unit of the form shown in this application designed for a given line capacity, the construction is comparatively bulky because of the fact that

each conductor of each line incoming and outgoing therefrom, is connected to one of the wipers engaging with the contact segments operated by the control element.

It is an object of the present invention, therefore, to provide improved switching apparatus of the general character described, wherein each of the switching units embodied therein is of extremely simple, rugged and compact arrangement, is economical in construction and faithful in operation, and wherein the units are susceptible of being easily mounted in a supporting frame, so that the capacity of an installed system utilizing the apparatus may be adjusted at will without disrupting the entire installation by adding or removing units from the frame.

More specifically, it is an object of the invention to provide a system of the above character wherein the control elements of the various units are operated by actuating means common to a plurality of the units.

In general, the objects as set forth above are in part attained in accordance with the present invention by providing switching apparatus comprising a plurality of switching units each including a movable circuit controlling element, a movable member for actuating the elements of the several units, means for selectively associating the elements with the actuating member to be actuated thereby, and means comprising a pair of heavy duty relays for imparting movement to the actuating member. More specifically, each switching unit circuit controlling element comprises a shaft biased to a normal position, such that the contact segments carried thereby are positioned intermediate two sets of wipers comprising resilient conductors fixedly mounted on the frame of the unit and arranged in two rows on either side of the contact segments. These wipers are adapted to be connected to the conductors of the lines outgoing from the unit and to be engaged by the contact segments when the control element is rotated in either of two directions to either of two off-normal positions individually corresponding to the sets of wipers. The conductors of the line incoming to the switch are adapted to be connected to the various contact segments by means comprising pigtail connectors electrically connected between the segments and the line conductor terminals. The various switching units are arranged in a row within a mounting frame which also carries the actuating member and the two solenoids for moving this member. This member is adapted to be associated in driving relation with selected ones

of the control elements respectively embodied in the switching units by clutching means individual to each unit and controlled by small relays of standard construction also individually embodied in each unit.

The novel features believed to be characteristic of the invention are set forth with particularity in the appended claims. The invention itself, however, both as to its organization and method of operation, together with further advantages and objects thereof, will best be understood by reference to the specification taken in connection with the accompanying drawing, in which Figure 1 illustrates switching apparatus constructed and arranged in accordance with the present invention and comprising a plurality of the improved switching units; Fig. 2 is a broken side view illustrating the details of one of the switching units shown in Fig. 1; Fig. 3 is a view partially in section taken along the lines 3—3 of Fig. 2; and Fig. 4 is a view illustrating the details of the clutching mechanism incorporated in the switching unit shown in Figs. 1 and 2.

Referring now more particularly to Fig. 1 of the drawing, the improved switching apparatus there shown and having embodied therein the features of the present invention comprises a frame 10, divided into two sections 11 and 12 for respectively accommodating a plurality of switching units 13, 14, 15, etc., and means common to these units for actuating the various circuit controlling elements thereof. The three units 13, 14, and 15 are shown as being mounted on the frame 10 within the section 11 by means comprising bolts 16 and 17 extending through the top and bottom members 8 and 9, respectively, of the frame 10. It is contemplated that with this arrangement the size of the section 11 for a frame 10 designed to accommodate the switching units for a particular installation shall be sufficient to accommodate the number of units ultimately required to serve the maximum estimated line capacity of the apparatus. Thus, if the apparatus is to be used in an automatic telephone system such, for example, as a system of the form disclosed and claimed in applicant's copending application Serial No. 168,726 filed October 13, 1937, having a calculated ultimate capacity of one thousand lines and a present capacity of four hundred lines, the section 11 will be made of sufficient size to accommodate the required number of switching units for setting up connections between one thousand lines. At the time the system is installed, however, only the number of units required to serve the four hundred lines will be placed in service, the remaining portion of the section being left blank and additional switching units being inserted therein from time to time as the size of the exchange progressively increases. By this arrangement and due to the exceptionally small size of each of the units, it is possible simply and economically to enlarge the capacity of a system embodying the units as the need for enlargement arises and without disrupting or in any way modifying the apparatus already in service.

The actuating means for the various circuit controlling elements embodied in the several switching units comprises a member 18, slidably mounted in openings provided in the end and intermediate members 19, 20 and 21 of the frame 10 and having rigidly supported thereon a magnetic piece 22, which forms the armature for each of two actuating magnets 23 and 24 mounted respectively on the frame members 20

and 21 by means of screws 25 and 26. The actuating member 18 is restrained in a normal position when both of the two magnets 23 and 24 are deenergized by means comprising coil springs 27 and 28 cooperating respectively with pivoted arms 29 and 30 which bear against opposite sides of the armature piece 22. The arm 29 is pivotally mounted on the upper member of the frame 10, and is limited in its movement to the left through the force exerted thereon by the spring 28 by a stop pin 31 also mounted on the frame 10 in any suitable manner. Similarly, the arm 30 is pivotally mounted on an extension 32 of the member 21 and is limited in its movement to the right under the force of the spring 28 by a stop pin 33 also supported on the frame 10. It will be observed that the member 18 is movable in either of two directions depending upon which of the two magnets 23 or 24 is energized. Thus, if the magnet 23 is energized it attracts the armature piece 22 to the left against the bias of the spring 28 to move the armature piece to the left. In a similar manner and with the member 18 and the armature piece 22 in the position shown, when the magnet 24 is energized these two members are moved to the right against the force exerted thereon by the spring 27. It is noted that the frame 10, the member 18 and the armature 22 are all constructed of magnetic material, such, for example, as iron, thereby to provide a low reluctance substantially closed magnetic circuit for the flux produced when either of the two magnets is energized and to enhance the force exerted on the armature piece 22 following energization of either of the two magnets.

Referring now more particularly to Figs. 2, 3 and 4 of the drawing, wherein the switching unit indicated generally at 13 is shown in greater detail, this unit comprises a frame 34 having right angularly bent end portions 35 and 36, between which the circuit controlling element comprising a shaft 37 is rotatably mounted. At its left end this shaft is supported by a bronze bearing cap 38, threaded into the end portion 36 and drilled to provide a bearing surface for the shaft. At its right end the shaft 37 is supported in a bearing surface formed by drilling the end portion 35 of the frame 34. Supported on and insulated from the shaft 37 by means comprising an insulating tube 39 are a plurality of contact segments 40 alternated with a plurality of insulating washers 41. For the purpose of fixedly positioning the segments 40 on the shaft 37 there is provided a fiber key 42 which is adapted to rest in a key slot formed in the shaft and to extend through suitably formed key-ways cut in the tube 39, the segments 40 and the washers 41. The segments 40 and insulating washers 41 are pressed together against an annular ring 43 by means comprising a nut 44 threaded on the right extremity of the shaft. It will be noted that the ring 43 is fixedly mounted on the shaft 37 by a pin 45 driven into a tapered drill hole extending through the ring and the shaft.

In assembling the elements referred to in the immediately preceding paragraph, the tube 39 is first slipped on the shaft 37 in abutting relation to the ring 43. Following this, the insulating washers 41 and segments 40 are slipped on the shaft over the insulating tube 39. The assembly is completed by inserting the key 42 in the key-way to align the various segments, and by screwing the nut 44 on the right end of the shaft to clamp the elements together, thereby to provide a rigid assembly.

Each of the contact segments 40 is electrically connected to a terminal 46 by a flexible pigtail connector 47, formed of copper braid or the like, soldered at its ends to the associated segment and terminal. As best shown in Fig. 3, the various terminals 46 are clamped between two members 48 and 49 constructed of insulating material by screws 50 extending through the two members noted and threaded into tapped drill holes provided in the frame 34. These terminals are adapted to be connected to the conductors forming the lines incoming to the switching unit. By this arrangement a switching unit of extremely small size for a given line capacity is obtained.

As shown more particularly in Figs. 2 and 3, each of the contact segments 40 is roughly triangular in shape, is rounded at its upper end, and is provided with a V-shaped groove, the sides of which form the contacting surfaces for engaging with either of two associated wipers. These wipers form two sets comprising respectively the resilient conductors 51 and 52 arranged in rows with their ends disposed on opposite sides of the contact segments. Preferably, these conductors are constructed of bronze or like resilient material and are supported on the frame 34 by clamping the same at the upper ends thereof between insulating members 53, 54 and 55. The members noted are clamped together and to the frame 34 by screws 56 extending therethrough and threaded into tapped drill holes provided in the frame 34. For the purpose of guiding the various wipers in their movement, there is provided intermediate the upper and lower ends thereof a guide member 57 of insulating material supported on the frame 34 by means comprising spacing members 58 located at each end of the member 57 and clamping screws 60. Each of the wipers 51 and 52 is tensioned or biased into engagement with this member and moves in a guide slot provided therein when engaged by its respective associated contact segment 40. The lower ends of the wipers 51 and 52 are curved outward to insure a smooth engagement with the respective associated contact segments when the segments are rotated into engagement therewith. It will be observed that the V-shaped groove provided in the engaging end of each of the segments insures a two-point contact between the segment and its associated wipers. It will be observed further that during rotation of the segments a slidable engagement occurs between each segment and its respective associated wipers to provide a self-cleaning action of the contacting surfaces. Normally the segments are restrained in the position shown in Fig. 3 of the drawing by means comprising a coil spring 61 connected between an arm 62 projecting from the annular ring 43 and an eye 63 clamped between the insulating members 48 and 49. From this normal position the shaft 37 is adapted to be rotated about its axis in either a clockwise or counterclockwise direction, thereby to bring the commutating segments 40 into engagement with the respective associated wipers 51 or 52 of the two wiper sets. Such rotation of the shaft 37 is accomplished through operation of the actuating member 18 from the normal position shown in Fig. 1 to one or the other of its two off-normal positions. To this end, and as best shown in Figs. 2 and 4, the member 18 is provided with a clutch projection 64 extending from the edge thereof, which projection is adapted to cooperate with a clutching element 65, slidable axially along the shaft 37, and normally restrained to the left out

of engagement with the projection 64 by a coil spring 67, interposed between the clutching element and the annular ring 43 and enclosing the shaft 37. A pin 66, extending through a drill hole provided in the shaft, engages the sides of a slot 68 cut in the shank portion 69 of the clutch element 65 to form a stop against which the element 65 is normally braced, to guide the element 65 in its movement axially along the shaft 37 and to provide means for mechanically coupling the element 65 with the shaft 37. The radially extending flange portion of the element 65 has formed at its lower end two fingers 70 and 71 within which the projection 64 on the member 18 is adapted to extend when the element 65 is moved to the right. It will be noted that the sides of the fingers 70 and 71 for engaging the projection 64 are rounded so that when the member 18 is moved in either of its directions of movement free and unrestricted movement of the element 65 to rotate the shaft 37 is obtained.

For the purpose of moving the clutching element 65 to the right to a position such that the projection 64 on the actuating member 18 extends between the fingers 70 and 71 there is provided a small relay or clutch magnet 72 mounted on an inturned portion 59 of the frame side member 36 by means of a screw 74. Pivotedly mounted at 75 in a slot formed in the member 36 is an armature 76 having mounted thereon an arm 77. This arm 77 is slotted at its lower end to form two fingers 79 and 80 which extend over the shaft 37 and are adapted to engage the left end of the shank 69 forming a part of the clutching element 65. The frame 34, and more particularly the side member 36 thereof, is formed of magnetic material, such, for example, as iron, whereby a substantially closed magnetic circuit, including the armature 36 is provided for the flux produced when the magnet 72 is energized. For purposes of control there is mounted on the frame side member 36 a contact spring assembly 81, comprising two or more contact springs clamped between insulating members as shown, and secured to the frame member 36 by a screw 82. The making and breaking of contact between the two springs comprising the assembly 81 is under the control of an arm 82 formed integrally with the armature 76 and provided with an insulating cap 83 for engaging the lower end of the right hand spring included in the spring assembly. In order to hold the shaft 37 and the segments carried thereby operated independently of the condition of the magnet 72 and following the energization of this magnet and one or the other of the magnets 23 and 24, the projection 64 is preferably made of square or triangular cross section and the inner opposite sides of the fingers 70 and 71 are provided with V-shaped grooves for lockingly engaging the opposite edges of the projection 64. By this arrangement the clutching element 65 may be held clutched to the projection 64 even though the magnet 72 is deenergized so long as the energized one of the magnets 23 and 24 is not deenergized.

In the operation of the switching unit described above and with the elements thereof in the positions illustrated in Figs. 1, 2, 3 and 4, if it be desired to connect the lines incoming to the switching unit 13 to the group of lines outgoing therefrom which terminate at the set of wipers including the wipers 51, the magnet 72 is first energized to bring the actuating member 18 into driving relationship with the shaft 37. Thus, when the magnet 72 is energized, it attracts

its armature 76 to make contact between the two springs of the assembly 81 and to pivot the arm 77 counterclockwise, thereby to slide the clutching element 65 along the shaft 37 against the bias of the spring 61 until it stands in a position such that the fingers 70 and 71 of the arm 77 have extending therebetween the projection 64 mounted on the actuating member 18. From a consideration of Figs. 3 and 4, it will be seen that the contact segments 40 must be rotated in a counterclockwise direction in order to connect the lines incoming to the unit to the outgoing lines terminating at the wipers 51. This means, of course, that the actuating member 18 must be moved to the right from the position shown in Fig. 4 and to the left from the position shown in Fig. 1, and consequently requires that the operating magnet 23 be energized. When this occurs, the finger 64 engages with the finger 70 of the clutching element 65 to rotate the shaft 37 in a counterclockwise direction and bring the contact segments 40 into engagement with their respective associated wipers 51, thereby to connect the lines incoming to the unit to the lines terminating at these wipers. The operating magnet 24 is maintained energized so long as the connection between these lines is desired. In this connection it is pointed out that the contact springs included in the assembly 81 may be utilized in completing holding circuits for maintaining either or both of the magnets 72 and 23 energized when the unit is in use. However, it is only necessary to maintain the magnet 23 energized in order to retain the unit in its operated position, as previously pointed out. To restore the elements of the unit to normal it is only necessary to deenergize the magnet 23, whereupon the clutching element 65 is disengaged from the actuating member 18 under the force exerted by the spring 67 subsequent to the return of the member 18 to its normal position by virtue of the force exerted thereon by the spring 28. As explained above, when the clutching element 65 is disengaged from the actuating member 18, the shaft 37 and the commutating segments 40 carried thereby are restored to their normal positions through the force exerted on the shaft 37 by the spring 61. From the preceding description it will be understood that if it is desired to connect the lines incoming to the switching unit to the lines outgoing therefrom which terminate at the wipers 52, the exact sequence of operations described above is followed with the exception that the operating magnet 24 is energized rather than the magnet 23.

As noted previously, the actuating member 18 is arranged selectively to operate the circuit controlling elements embodied in all of the switching units mounted within the section 11 of the frame 10. This is accomplished by providing projections, corresponding to the projection 64 for the unit 13, at correctly spaced intervals along the actuating member 18, which projections are adapted individually to cooperate with clutching elements individually included in each of the switching units and corresponding to the element 65 of the unit 13, when the units are mounted in their correct positions within the section 11 of the frame 10.

Although the switching units 13, 14, 15, etc., may be constructed of any given size it is specifically contemplated that each thereof shall have an outgoing line capacity of forty lines of three conductors each. Obviously a unit of this capacity requires sixty wipers 51, sixty wipers 52,

and sixty contact segments 40. Where, as in the system disclosed in the above referred to co-pending application of applicant, only a single incoming line to each unit is provided, three multiples must necessarily be carried between the segments 40 and connected to the conductors of this line.

While there has been described what is at present considered to be the preferred embodiment of the invention, it will be understood that various modifications may be made in the structure thereof, and it is contemplated in the appended claims to cover all such modifications as fall within the true spirit and scope of the invention.

I claim:

1. Switching apparatus comprising a plurality of switching units each including a circuit controlling element comprising a rotatable shaft, a member having a normal position and movable to an off-normal position to actuate said shafts, said shafts normally being non-responsive to movement of said member to said off-normal position, clutch projections on said member and corresponding to said units, a clutching element mounted on each of said shafts normally restrained in one position and having fingers adapted to cooperate with the associated clutch projection to establish a driving connection between the shaft and said member, a clutch magnet included in each unit for moving the clutching element of the same unit into clutching relation with its associated clutch projection, a magnet adapted to be energized to move said member from said normal position to said off-normal position, and means for returning said member to its normal position following the energization and subsequent deenergization of said magnet.

2. Switching apparatus comprising a plurality of switching units each including a circuit controlling element selectively movable from a normal position in either of two directions, a movable member for actuating said elements, said elements normally being non-responsive to movement of said member, means for selectively associating said elements with said member to be actuated thereby, means for moving said member in one direction to move any of said elements associated therewith from the normal position in one of said directions of movement, and means for moving said member in another direction to move any of said elements associated therewith from the normal position in the other of said directions of movement.

3. Switching apparatus comprising a plurality of switching units each including two groups of wipers, a circuit controlling element and contact segments mounted on said element, each of said elements being movable in two directions from a normal position to either of two off-normal positions to bring the segments mounted thereon into engagement with the respective associated wipers of one or the other of its associated wiper groups, a movable member for actuating said elements, said elements normally being non-responsive to movement of said member, means for selectively associating said elements with said member to be actuated thereby, means for moving said member in one direction to move any of the elements associated therewith in one of said directions of movement from the normal position to one of said off-normal positions, and means for moving said member in another direction to move any of said elements associated therewith in the other of said directions of move-

ment from the normal position to the other of said off-normal positions.

4. Switching apparatus comprising a plurality of switching units each including two groups of wipers, a circuit controlling element and contact segments mounted on said element, each of said elements being movable in two directions from a normal position to either of two off-normal positions to bring the segments mounted thereon into engagement with the respective associated wipers of one or the other of its associated wiper groups, a movable member for actuating said elements, said elements normally being non-responsive to movement of said member, means for selectively associating said elements with said member to be actuated thereby, said last-mentioned means comprising a clutch mechanism included in each unit and a clutch magnet included in each unit for operating the clutch mechanism of the same unit, means for moving said member in one direction to move any of the elements associated therewith in one of said directions of movement from the normal position to one of said off-normal positions, and means for moving said member in another direction to move any of said elements associated therewith in the other of said directions of movement from the normal position to the other of said off-normal positions.

5. Switching apparatus comprising a plurality of switching units each including two groups of wipers, a rotatable shaft and contact segments mounted on said shaft; each of said shafts being rotatable in one direction from a normal position to one off-normal position to bring the segments mounted thereon into engagement with the respective associated wipers of one of its associated wiper groups and being rotatable in the other direction from said normal position to a second off-normal position to bring the segments mounted thereon into engagement with the respective associated wipers of the other of its associated wiper groups, a movable member for actuating said shafts, said shafts normally being non-responsive to movement of said member, means for selectively associating said shafts with said member to be actuated thereby, means for moving said member in one direction to rotate any of the shafts associated in driving relationship therewith in one of said directions from the normal position to one of said off-normal positions, and means for moving said member in another direction to rotate any of the shafts associated in driving relationship therewith in the other of said directions from the normal position to the other of said off-normal positions.

6. Switching apparatus comprising a plurality of switching units each including two groups of wipers, a rotatable shaft and contact segments mounted on said shaft; each of said shafts being rotatable in one direction from a normal position to one off-normal position to bring the segments mounted thereon into engagement with the respective associated wipers of one of its associated wiper groups and being rotatable in the other direction from said normal position to a second off-normal position to bring the segments mounted thereon into engagement with the respective associated wipers of the other of its associated wiper groups, a movable member for actuating said shafts, said shafts normally being non-responsive to movement of said member, means for selectively associating said shafts with said member to be actuated thereby, said last-mentioned means comprising a clutch

mechanism included in each unit and a clutch magnet included in each unit for operating the clutch mechanism of the same unit, means for moving said member in one direction to rotate any of the shafts associated in driving relationship therewith in one of said directions from the normal position to one of said off-normal positions, and means for moving said member in another direction to rotate any of the shafts associated in driving relationship therewith in the other of said directions from the normal position to the other of said off-normal positions.

7. Switching apparatus comprising a plurality of switching units each including two groups of wipers, a rotatable shaft and contact segments mounted on said shaft; each of said shafts being rotatable in one direction from a normal position to one off-normal position to bring the segments mounted thereon into engagement with the respective associated wipers of one of its associated wiper groups and being rotatable in the other direction from said normal position to a second off-normal position to bring the segments mounted thereon into engagement with the respective associated wipers of the other of its associated wiper groups, a movable member for actuating said shafts, said shafts normally being non-responsive to movement of said member, clutch projections on said member and corresponding to said units, a clutching element mounted on each of said shafts normally restrained in one position and having fingers adapted to cooperate with the associated clutch projection to establish a driving connection between the shaft and said member, a clutch magnet included in each unit for moving the clutching element of the same unit into clutching relation with its associated clutch projection, means for moving said member in one direction to rotate any of the shafts associated in driving relationship therewith in one of said directions from the normal position to one of said off-normal positions, and means for moving said member in another direction to rotate any of the shafts associated in driving relationship therewith in the other of said directions from the normal position to the other of said off-normal positions.

8. Switching apparatus comprising a plurality of switching units each including two groups of wipers, a rotatable shaft and contact segments mounted on said shaft; each of said shafts being rotatable in one direction from a normal position to one off-normal position to bring the segments mounted thereon into engagement with the respective associated wipers of one of its associated wiper groups and being rotatable in the other direction from said normal position to a second off-normal position to bring the segments mounted thereon into engagement with the respective associated wipers of the other of its associated wiper groups, a movable member for actuating said shafts, said shafts normally being non-responsive to movement of said member, clutch projections on said member and corresponding to said units, a clutching element mounted on each of said shafts normally restrained in one position and having fingers adapted to cooperate with the associated clutch projection to establish a driving connection between the shaft and said member, a clutch magnet included in each unit for moving the clutching element of the same unit into clutching relation with its associated clutch projection, a magnet adapted to be energized to move said actuating member in one direction thereby to 75

- rotate any of the shafts associated in driving relationship therewith in one of said directions of movement from the normal position to one of said off-normal positions, a second magnet adapted to be energized to move said actuating member in a second direction thereby to rotate any of the shafts associated in driving relationship therewith in the other of said directions from the normal position to the other of said off-normal positions, and means for returning said actuating member to its normal position following the energization and subsequent deenergization of either of said magnets. 5
9. Switching apparatus comprising a switching unit including a circuit controlling element selectively movable in either of two opposite directions, a movable member for actuating said element, said element normally being non-responsive to movement of said member, means for 10 associating said element with said member to be actuated thereby, means for moving said member in one direction to move said element, when associated with said member, in one of said directions of movement, and means for moving 15 said member in another direction of movement to move said element, when associated with said member, in the other of said directions of movement. 20
10. Switching apparatus comprising a switching unit including a circuit controlling element selectively movable in either of two directions, a movable member for actuating said element, said element normally being non-responsive to movement of said member, means for associating 25 said element with said member to be actuated thereby, said last-mentioned means comprising a clutch mechanism included in said unit and a clutch magnet included in said unit for operating said clutch mechanism, means for moving 30 said member in one direction to move said element, when associated with said member, in one of said directions, and means for moving said member in another direction of movement to move said element, when associated with said member, in the other of said directions of movement. 35
11. Switching apparatus comprising a plurality of switching units each including a circuit-controlling element selectively movable in either of two directions, an operating bar mounted for movement from a normal position in either direction along its longitudinal axis to actuate 40 said elements in their respective two directions 45
- of movement, said elements normally being non-responsive to movement of said bar, means for selectively associating said elements with said bar to be actuated thereby, means for moving said bar from its normal position longitudinally in one direction to move any of said elements associated therewith in one of the two directions of movement thereof, means for moving said bar from said normal position longitudinally in the other direction to move any of said elements 50 associated therewith in the other of the two directions of movement thereof, and means normally restraining said bar in said normal position. 5
12. Switching apparatus comprising a frame, a plurality of switching units mounted on said frame, each of said units including a circuit-controlling element comprising a rotatable shaft selectively rotatable in either of two directions, said shafts being arranged in parallel and extending in the same direction, a clutching element slidably mounted on one and the same end of each of said shafts and normally restrained in one position, each of said clutching elements including a pair of fingers, an operating bar slidably mounted on said frame and arranged to be moved from a normal position in either of two directions along its longitudinal axis and transversely with respect to said shaft, clutch projections extending from said bar at spaced intervals and individually corresponding to the clutching elements of said switching units, a clutch magnet included in each unit for moving the clutching element of the same unit from said one position to bring the fingers of the associated clutching element into clutching relation with the corresponding clutch projection, a magnet adapted to be energized to move said operating bar from its normal position longitudinally in one direction thereby to rotate any of the shafts associated in driving relationship therewith in one of their two directions of movement, a second magnet adapted to be energized to move said operating bar from said normal position longitudinally in the other direction thereby to rotate any of the shafts associated in driving relationship therewith in the other of their two directions of movement, and means for returning said operating bar to its normal position following the energization and subsequent deenergization of either of said magnets. 15 20 25 30 35 40 45 50 5
